2,386,650

MOTHER SHIP

Leroy V. Bell, Wakefield, R. I.

Application March 11, 1943, Serial No. 478,805

5 Claims. (Cl. 114—43.5)

My invention relates to naval craft, and has among its objects and advantages the provision of an improved mother ship provided with novel means for housing and transporting a large number of smaller boats, such as submarines, torpedo boats and the like, wherein novel means are incorporated to facilitate loading, storage and launching of the smaller boats.

In the accompanying drawings:

Figure 1 is a side view of the mother boat partly in section.

Figure 2 is a stern end view.

Figure 3 is a sectional view taken along the line 3—3 of Figure 1.

Figure 4 is a diagrammatic plan view of the mother boat.

Figure 5 is an enlarged horizontal plan view of the stern end.

Figure 6 is an enlarged vertical sectional view of the stern end.

Figure 7 is a sectional view along the line 7—7 of Figure 5.

Figure 8 is a sectional view taken along the line 8—8 of Figure 5.

Figure 9 is a sectional view along the line 9—9 of Figure 5.

Figure 10 is a sectional view along the line 10—10 of Figure 5.

Figure 11 is an enlarged plan view of a turntable.

Figure 12 is an elevational view of the structure of Figure 11.

Figure 13 is an enlarged sectional view taken along the line 13—13 of Figure 11.

Figure 14 is an enlarged sectional view taken along the line 14—14 of Figure 11.

Figure 15 is a plan view of boat balancing ramps.

Figure 16 is a side view.

Figure 17 is a face view of stern doors.

Figure 18 is a view taken from the position indicated by line 18—18 of Figure 17, illustrating door actuating means.

Figure 19 is a view of side doors.

Figure 20 is a diagrammatic view illustrating operating means for the doors of Figure 19.

Figure 21 is a diagrammatic view illustrating the manner in which boats of different types are supported on a cradle.

Figure 22 is a top plan view, and

Figure 23 is an end view.

In the embodiment of the invention selected for illustration, I made use of a mother ship 12, wherein the hull 14 is provided with door openings 16 upon opposite sides thereof. Each open-

ing is normally closed by a hinged door 18. Small boats may pass through the openings 16 and into upwardly inclined channels 20. A channel is provided for each door opening 16. Tracks 22 are mounted on the bottoms of the inclined channels on which boat carrying cradles 24 are adapted to run for conveying the boats onto tracks 26 on a turntable 28. The outer or lower ends of the channels 20 are submerged sufficiently far to permit the boats to pass partly through the door openings on their own power, at which time the boats are easily loaded on the cradles.

Figure 5 illustrates tracks 30 running longitudinally of the ship 12 forwardly and rearwardly of the ship and converging toward the turntable 28, so that the boat loaded cradles loaded on the turntable may be transferred onto any of the tracks 30 and stored on the deck 32.

The turntable 28 comprises a circular frame structure 34 mounted on wheels 36 running on circular rails 38. Two ramps 40 are mounted to pivot on a supporting shaft 42. This shaft is located intermediate the ends of the ramps 40, the ramps being located in parallel relationship on opposite sides of the axis of the frame structure 34. One track or two rails 26 are mounted on each ramp 40. These rails are of the same gauge as the rails 30, so that boat laden cradles on the tracks 26 may be easily transferred onto the tracks 30.

Means for tilting the ramps 40 to facilitate loading of boats on the turntable, such as the boat 44 of Figure 3, comprises two large wheels 46 mounted at diametrically opposite points on the frame structure 34. Each wheel is provided with handles 48. Each wheel 46 is connected with one ramp 40 so that the ramps may be independently operated.

In Figure 13, the hand wheel 46 is rotatably mounted on a pedestal 50 provided with a gear box 52 at its upper end. A shaft 54 is fixed to the wheel 46 and is provided with a bevel gear 56 arranged in mesh with a bevel gear 58 mounted on a support 60 for rotation about a vertical axis.

This bevel gear is fixed to a pinion 62 meshing with two pinions 64. Each pinion 64 is fixed to a vertical shaft 66 which extend downwardly to points beneath the frame structure 34. The wheels 46 and their associated structure are identical, so that the description of one will apply to both.

In Figures 13 and 14, the lower ends of the shafts 66 are threaded at 68. Right hand threads are provided on one shaft and left hand threads on the other. A body 70 is threadedly

connected with each shaft, each body being provided with pins 72. Two levers 74 are located underneath the frame 34 and are pivotally supported intermediate their ends in bearings 76. Each lever is provided with two straps 78 at one end, these straps being slotted at 80 for the reception of the two pins 72 on one of the bodies 70. A link 82 is pivotally connected at 84 with the opposite end of each beam 74, and the upper end of the link is pivotally connected at 86 with one ramp 40. The pivotal connections 86 are located on opposite sides of the shaft 42, see Figure 11, so that rotation of the wheel 46 will cause one body 70 to climb upwardly on one shaft 66 and the other body 70 downwardly on the other shaft. Such movement of the bodies 70 impart pivotal movement to the beam 74, the beams pivoting in opposite directions to rock the ramp 40 about the axis of the shaft 42. Thus the ramps 40 may be adjusted easily to declining positions to facilitate loading of the boats. The ramps 40 may be inclined in the same direction simultaneously or reversely. When inclined, the low ends of the ramps extend sufficiently far in the water to permit the boat 44 to be easily loaded on the cradle on the rails 26.

Figures 19 and 20 illustrate the manner in which the doors 18 are operated. Two doors 18 are grouped for each door opening 16. The two doors at each opening are hinged at their far edges. Both groups are operated simultaneously, the doors on one side of the hull being independent of the doors on the other side.

In Figure 20, a horizontal screw 88 is rotatably mounted in supports 90 and 92. A gear 94 is fixed to the screw 88 for driving connection with a suitable power mechanism (not shown). A sleeve 96 is threadedly connected with the screw 88. Two diverging rods 98 are attached to the sleeve 96 and to sleeves 100 slidably mounted on parallel guide rods 102. These guide rods are fixedly supported in mounts 104 attached to a suitable supporting structure in the ship.

Two rigid links 106 are pivotally connected with each sleeve 100. Each link 106 is pivotally connected at 108 with one door 18 near its edge opposite the hinges of that door. Thus the doors 18 may be opened and closed through rotation of the screw 88.

In Figures 5, 9 and 10, four declining ramps 110, 112, 114, and 116 are located upon opposite sides of the stern end of the hull. The ramps 110 and 116 are provided with track rails 118 constituting continuations of certain of the tracks 30. All the ramps 112 and 114 include pivoted floors 120 each provided with two track rails 122 constituting continuations of certain of the tracks 30 in the stern end of the boat. All the floors 120 are of the same construction. In Figures 15 and 16, the floors 120 are pivotally mounted intermediate their ends on shafts 124. The shafts 124 are located transversely of the hull. Boats may be loaded onto the track rails 118 and 122 through stern door openings 126 and 128, respectively.

Figures 15 and 16 illustrate a wheel 130 for each floor 120. These wheels are similar to the wheels 46, the difference residing in the fact that each wheel rotates one screw 132 having a sleeve 134 threadedly connected therewith. A lever 136 is pivotally mounted intermediate its ends to a fixed support 138, and the other end of the lever has a link connection 140 with one end of the floor 120. Thus the floor 120 may be pivoted to different positions through rota-

tion of its respective wheel 130. The floors 120 are independently operated.

Boats are easily loaded onto the floors 120 by pivoting the floors to the dotted line position of Figure 16, at which time the boats may be easily transferred onto the tracks 30 aligning with those floors. The floors 120 may also be employed to carry boats when the floors are in their horizontal positions, so that the ramps 112 and 114 also function as storage facilities.

All the ramps 110 through 116 decline rearwardly so as to provide channels 142 into which the boats are easily floated best illustrated in Figure 10.

Two doors 144 are provided for each door opening 128. The doors 144 for each door opening is independent of the other two doors. In Figure 18, a sleeve 146 is threadedly connected with a screw 148 rotatably supported in suitable supports 150. Two links 152 are pivotally connected with the sleeve 146, and each link is pivotally connected at 154 with one door 144, the two doors in each group being hinged at 156 to bring their free edges into abutting engagement in their closed position. A power operated gear 158 is fixed to the screw 148, which gear may be driven by a suitable power device (not shown).

Columns 160 are erected at suitable intervals along the two sides of the tracks 30, which columns constitute means for supporting the boats and cradles on the tracks, particularly when the ship is riding heavy waves. Figure 23 illustrates the arrangement of the columns 160 with respect to one of the tracks 30. Tie lines may be employed for more firmly anchoring the boats and the cradles to the columns.

Figures 21, 22 and 23 illustrate one of the cradles 24. This cradle includes a frame 162 provided with flanged wheels 164 which run on the track 30. Pull lines 166 are attached to the frame 162, and lines 168 may connect with the pull lines 166 to tie the boat to the cradle. Various types of boats are illustrated diagrammatically in Figure 21 in association with the cradle 24 illustrated therein.

In Figure 16, a cage 170 is mounted on an overhead rail structure 172. These cages are power operated. Rail structures 172 are arranged above all the tracks 30 so that the boat laden cradles may be pulled along the tracks throughout their entire lengths. Such power operated cages are old and well known in the art.

A water duct 174 opens through the bottom of the boat as at 116 in Figure 6. A power driven screw 178 is arranged in the duct 174 for conveying water rearwardly of the boat for passage through branch ducts 180 and into the channels 20 and 142 to insure an ample supply of water for the boats. While the boats 44 can best be loaded through the side channels 20 when the mother ship is standing still, the boats may be easily loaded through the channels 142 even though the mother ship is under full speed. This is also true with respect to launching of the boats.

The turntable 28 is located in such relation to all the tracks as to constitute a transfer point facilitating storage of the boats, as well as transfer of the boats to different tracks, depending upon the needs of fast changing operating conditions. The drawings illustrate the turntable 28 in the stern region of the ship. The ship is also provided with a second turntable in its forward part for coaction with the forwardly ex-

tending tracks 30. Small doors 182 are provided for the two side ramps 110. These doors may be manually operated, or power controlled, as desired. An upper deck 184 is provided for the storage of airplanes. The mother ship propellers are indicated at 186.

Without further elaboration, the foregoing will so fully explain my invention, that others may, by applying current knowledge, readily adapt the same for use under various conditions of service.

I claim:

1. A mother ship construction for receiving, storing and launching small boats, comprising a hull formed with a plurality of door openings, partially below the water line to receive and discharge small boats therethrough, a deck-like structure within the hull formed with a turntable section, tracks on the turntable section, means for tilting the tracks on the turntable section, inclined channels leading from the turntable section to the doors and having tracks with which the tracks of the turntable are adapted to selectively register when tilted, cradles on the tracks for receiving boats thereon, means for moving the cradles to draw boats up the tracks in the channels and onto the turntable, storage deck-like structures having tracks selectively aligning with those on the turntable, doors for the hull openings, means for delivering water to boats on the cradles in the channels in the area

about the doors to facilitate launching and receiving boats on the cradles, said means including water ducts and propellers within the hull.

2. The invention as defined in claim 1 wherein the deck-like structure and turntable are above water level, and the openings in the hull are partially below water level, and the channels are inclined from the level of the deck-like structure to the level of the openings.

10 3. The invention as defined in claim 1 wherein the turntable is formed with independently tiltable sections, means for tilting the sections and the turntable tracks carried on the sections, and wherein said water ducts have intakes below water level, and said ducts lead to the channels to maintain therein a desired water level in the area adjacent the doors.

15 4. The invention as defined in claim 1 wherein the storage tracks extend longitudinally of the hull and certain of which are curved to align with the tracks of the turntable, and wherein said channels and the tracks therein extend both longitudinally and transversely of the hull, and the hull is provided with openings in the sides and stern communicating therewith.

20 5. The invention as defined in claim 1 wherein means are provided for tilting the cradles in certain of the channels, and wherein supporting columns are disposed along the storage tracks for the boats stored thereon.

30

LERoy V. BELL.
